UNITED STATES PATENT OFFICE.

FRED D. DOTY, OF OCEAN CITY, NEW JERSEY.

BOAT.

1,203,506.

Specification of Letters Patent. Patented Oct. 31, 1916.

Application filed August 23, 1915. Serial No. 46,878.

To all whom it may concern:

Be it known that I, FRED D. DOTY, a citizen of the United States, and a resident of Ocean City, Cape May county, New Jersey, 5 have invented certain Improvements in Boats, of which the following is a specification.

My invention relates to boats of light draft for employment in shallow water-ways; and 10 one object of my invention is to provide a shallow draft boat with improved means for propelling the same, which propelling means are mounted at the forward part of the boat.

15 While my improved propelling means may be adapted for use with various types of boats, such as canal boats, freight boats, passenger boats and the like, I have shown the same in connection with a shallow, light 20 draft passenger boat designed more particularly for use in canals, inland water-ways, tidal estuaries and the like where the presence of bars, low water, or other obstructions to navigation would interfere with 25 the employment of boats having a greater draft.

A further object of my invention is to provide a boat having propelling means mounted at the forward end and a substantially 30 flat bottom provided with bottom channels whereby any waves produced by the paddle wheels will be carried rearward under the boat and thereby avoid all danger of destroying the banks of the 35 stream, canal, or other water-way in which such boat is operated.

These and other features of my invention are more fully described hereinafter, reference being had to the accompanying 40 drawings, in which:

Figure 1, is a side elevation, partly in section, of a light draft boat made in accordance with my invention; Fig. 2, is a plan view of the same; Fig. 3, is a cross sectional view on the line 3—3, Fig. 1, illustrating the driving mechanism on a larger scale, and Fig. 4, is a rear elevation of the boat.

The hull 1 of my improved boat is of the 50 "Garvey" type, having a rounded bow 2, square stern 3, and a substantially flat bottom 4 extending from end to end of the same. Such hull is provided with a suitable deck 5, pilot house 6, cabins 7, and 55 other fixtures suitable or common to boats of this character, which features are indi-

cated more or less diagrammatically in the accompanying drawings.

The central portion of the bottom rises gradually toward the stern from the point 60 α , with a pair of keels or keelsons 8 extending in the plane of the bottom as far as the rudder posts 9, of the rudders 10, and at the front the bottom gradually rises to meet the rounded bow. For the purpose of propelling this boat, I provide a plurality of 65 paddle wheels 11 at the forward part of the boat, and these paddle wheels may be mounted directly beneath the pilot house; being disposed within a well or chamber 70 12, entirely closed at the top and sides but open at the bottom; such well or chamber communicating with an inlet passageway 13 at the forward end of the boat above the water-line. From the well or chamber 75 12, a passageway 14 is extended rearwardly, gradually decreasing in height and merging with the bottom of the boat, in the manner clearly shown in Fig. 1; the keels or keelsons 8 forming the sides of such channel. 80 By this construction, only limited portions of the boat forward of the paddle wheels are below the water-line, and those portions are at the sides of the boat.

My improved paddle wheels 11 are mounted on shafts 15 inclined at an angle with respect to the horizontal, as clearly shown in Fig. 3, such wheels having suitable bearings 16 carried by side portions of the hull, and thrust bearings 17 carried by a suitable 90 supporting structure 18 disposed in the well or chamber 12 in line with the longitudinal axis of the hull. In the present instance said propeller wheels are driven by a shaft 19 centrally mounted with respect to the 95 longitudinal axis of the boat and having a worm 20 driving worm wheels 21 mounted on the inner ends of the propeller shafts. Any suitable prime mover may be employed for driving the worm shaft, and it will be 100 understood, of course, that suitable clutches and reversing gear will be supplied so that the boat may be driven forward or backward as desired. In lieu of the worm and worm shaft, I may drive the propeller shaft 105 by any usual form of power transmitting means, bevel gearing, separate shafts, chains, and chain wells, &c., all of which mechanism is within the scope of my invention.

The propeller wheels are made up of hubs 110 11^a, having spokes 11^b suitably braced, and carrying at their ends the paddles or blades

11° which are set so as to enter and leave the water at an angle with respect to the horizontal; one corner of the blades first entering the water and the blades being in full engagement with the water when at the center of their stroke, as clearly shown in Fig. 3. In this inclined arrangement of the propellers there is less drag since the paddles or blades are not required to lift as great an amount of water as is required by the use of propeller wheels as ordinarily arranged.

I preferably provide two rudders 10 connected by suitable means so as to move in unison, with suitable tiller mechanism connected with operating means within the pilot house and an independent tiller 22 for direct operation at the stern.

As the under portion of the hull at the bow of the boat is substantially above the level of the water-line, there is no portion of the boat upon which the indrawn water can drag. The water usually leaves the propellers within the well or chamber 12 in a turbulent or churned condition, filled with bubbles of air, over which the boat immediately passes; such bubbles being confined by the passageway 14. The bottom of the boat is further provided with the pair of keels or keelsons 8, so as to provide a continuation of the channel 14 for the rearward passage of the water. By this arrangement, the air-containing and broken water is retained under the boat for its full length and discharges from the stern only; and increased buoyancy of the boat is the result.

The water beneath the bow of the boat is drawn under the bottom through the channel or inlet passageway 13 by reason of the forward mounting of the paddle wheels instead of being forced outward from the boat, as it would be if the propellers were otherwise mounted. As the boat is built with its broadest beam about one-third aft from the bow in order to support the additional weight, the water is caused to fall in toward the stern and will be quieted down by the escaping air from under the stern, thus preventing any sidewash on the banks of a small stream or canal.

By preference, the exhaust from an explosion engine, when used, may be let out through pipes running into the well 12 or channel 14 along the inside of either keel or keelson 8, which pipes open toward the stern. I am thus able to utilize any power present in the thrust of the exhaust to aid in the propulsion besides supplying additional air or gases under the boat to quiet the water stirred up by the propellers and silencing any noise from the engine.

I claim:

1. The combination, in a boat, of a hull having a hollow space disposed forward of

the center of the boat and open to the water with inlet and outlet channels for water fore and aft of said hollow space; the upper wall of the forward channel being substantially above the surface of the water while the upper wall of the after channel slopes downwardly below the surface of the water and forms the bottom of the boat, a plurality of paddle wheels mounted in said hollow space, and a plurality of keels carried by said hull and forming a channel rearwardly from said paddle wheel space.

2. The combination, in a boat, of a hull having a hollow space disposed forward of the center of the boat and open to the water with inlet and outlet channels for water fore and aft of said hollow space; the upper wall of the forward channel being substantially above the surface of the water while the upper wall of the after channel slopes downwardly below the surface of the water and forms the bottom of the boat, a plurality of paddle wheels mounted in said hollow space, each of said paddle wheels being mounted on an axis set at an angle with respect to the horizontal, paddles carried by each wheel which enter and leave the water at an angle, and a plurality of keels carried by said hull and forming a channel rearwardly from said paddle wheel space.

3. The combination, in a boat, of a hull having a hollow space forward of the center of the boat and extending above the deck; said space being open to the water with inlet and outlet channels for water fore and aft of said hollow space; the upper wall of the forward channel being substantially above the surface of the water, a plurality of paddle wheels mounted in said hollow space, each of said paddle wheels being mounted on an axis set at an angle with respect to the horizontal, paddles carried by each wheel which enter and leave the water at an angle to the horizontal, said hull having its bottom aft of the propellers gradually deepened and then rising to a point above the surface of the water, with a plurality of keels carried by said hull and providing a channel leading rearwardly from the paddle wheel space.

4. The combination, in a boat, of a hull having a hollow space open to the water at the forward part of the same, the central portion of the bottom of the hull at the bow being substantially above the surface of the water and providing a channel leading to said hollow space, a plurality of paddle wheels mounted in said space and disposed for engagement with the surface of the water, each of said paddle wheels being mounted on an axis set at an angle with respect to the horizontal and having paddles which enter and leave the water at an angle to the horizontal, worm gearing for driving said paddle wheels, said hull hav-

ing its bottom aft of the propellers gradually deepened and then rising to a point above the surface of the water at its stern, with keels carried by said hull and providing channels; the bottom of said hull adjacent the central channel and for the greater part of its length being flat.

5. The combination, in a boat, of a hull having a hollow space forward of the center of the boat and open to the water with inlet and outlet channels for water fore and aft of said hollow space; the upper wall of the forward channel being substantially above the surface of the water while the upper 10 wall of the after channel slopes downwardly below the surface of the water and forms the bottom of the boat, a plurality of paddle wheels mounted in said hollow space, each of said paddle wheels being mounted on an 15 axis set at an angle to the horizontal, and means for driving said paddle wheels.

6. The combination, in a boat, of a hull having a hollow space forward of the center of the boat and open to the water with inlet and outlet channels for water fore and aft 25 of said hollow space; the upper wall of the forward channel being substantially above the surface of the water while the upper wall of the after channel slopes downwardly below the surface of the water and 30 forms the bottom of the boat, a plurality of paddle wheels mounted in said hollow space, each of said paddle wheels being mounted on an axis set at an angle with respect to the horizontal, paddles carried 35 by said wheels which enter and leave the water at an angle, driving means paralleling the longitudinal axis of the hull, and worm gearing actuated by said driving means and operatively connected to the paddle 40 wheels for driving the latter.

FRED D. DOTY.
